UNITED STATES PATENT OFFICE.

LEWIS JORDAN, OF SPENCER, IOWA.

DESIGN FOR A TOOTHPICK-HOLDER.

44,444.

Specification for Design.

Patented Aug. 5, 1913.

Application filed May 16, 1913. Serial No. 768,165. Term of patent 7 years.

To all whom it may concern:

Be it known that I, LEWIS JORDAN, a citizen of the United States, residing at Spencer, in the county of Clay and State of Iowa, have invented a new, original, and ornamental Design for Toothpick-Holders, of which the following is a specification, reference being had to the accompanying drawing, constituting a part thereof.

The figure is a perspective view of a tooth pick holder, showing my new design.

I claim:

The ornamental design for a tooth pick holder, as shown.

LEWIS JORDAN.
